ALARM LOCK

Gaetano Maida, Jr., New York, N. Y.

Application November 15, 1938, Serial No. 240,448

1 Claim. (Cl. 200—55)

This invention relates to locks of all kinds, and its object is to provide a novel circuit-closing means contained within the lock, whereby an audible or visual alarm of any kind may be actuated as soon as the lock is opened.

The above and other objects will become apparent in the description below, in which characters of reference refer to like-named parts in the accompanying drawing.

10 Referring briefly to the drawing,

Figure 1 is a view illustrating the alarm clock applied to a house door.

Figure 2 is a view of the lock with its cover plate removed, showing the hasp in locked position.

Figure 3 is a view similar to Figure 2, showing the hasp in sprung position.

Figure 4 is an enlarged fragmentary view, partly in section, of the left-hand side of the lock of Figure 3.

Figure 5 is a cross-sectional view taken on the line 5—5 of Figure 2.

Figure 6 is a fragmentary cross-sectional taken on the line 6—6 of Figure 4.

25 Referring in detail to the drawing, the numeral 10 represents the annular housing of a hasp lock having the two cover plates 11 and 12, into which the key 13 is, as is customary, insertable from the bottom. The bolt 14 has its arm 15 slidably mounted in an opening in the housing 10, and a coiled spring 16 normally urges the arm 15 upward. As the lock per se may be of any standard type of construction, and it is not desired to claim any part of the same, further unimportant details of the lock per se will not be described.

30 The arm 15 of the bolt 14, however, is modified from the standard construction by providing a peripheral groove 17 thereon intermediate its length. Within the housing 10, one end of a strip 40 of firm insulation 18 is anchored to the roof of the housing by a screw or rivet 19, with one end of a spring contact finger 20 secured between the rivet 19 and the insulation 18. At its other end the strip 18 has a rivet 21 passing therethrough, and on its lower end a metallic contact button 22 is integral with the rivet 21. On its top end the rivet 21 retains a spring terminal 23 against the strip 18, in electrical contact with the rivet 21 and the button 22. The free end of the finger 20 is concavely rounded to provide a yoke 24 which registers loosely in the groove 17 of the hasp arm 15. An insulated wire 25 has its end attached to the spring terminal 23, and passes through a hollow metallic tube 27

5 into an armored sleeve 26 out of the housing 10, through an opening in the latter. The tube 27 has a flange 28 on its free end, by means of which it is prevented from being pulled through the said opening, and the protruding end of its stem has a flange 30 rotatably locked in the nut 29 on the end of the armored sleeve 26. It is thus obvious that the sleeve 26 cannot be detached from the lock housing without cutting through the sleeve.

10 The spring finger 20 is, as is apparent, grounded to the housing 10 by the rivet 19; the armored sleeve 26, as is also apparent, is also in electrical contact with the housing 10 and is used as one of the conductors of the circuit leading from the 15 lock to the alarm unit. The latter comprises a relay 31 having one terminal lead by a wire 32 to the sleeve 26 and its other terminal lead by a wire 33 to one terminal of the battery 33; the other battery terminal is connected by a wire 20 34 to the wire 25. It is thus apparent that, when the circuit between the finger 20 and the button 22 is closed, the relay 31 will be actuated. The armature 35 of the relay is pivoted at its lower end, at 36. A coiled spring 37 is anchored at its 25 lower end at a point 39 beyond the pivot 36 and has its upper end attached at 38 to the armature; it is to be noted that the points 38, 36, and 39 are in alignment when the armature is in its inactive position, so that the spring 37 will 30 tend to preserve that position. Upon energization of the relay, the armature will swing toward the relay to bring its head 40 against the contact 41, and in the latter position of the armature the spring 37 will also tend to preserve the 35 position, so that in order to open the contact between the members 40 and 41 it will be necessary to move the armature back by hand. Thus, once the relay is energized the members 40 and 41 are brought into mutual contact and will remain so until separated by hand.

40 The armature 40 is connected by the wire 42 to one terminal of the alarm 43; the contact 41 is connected by a wire 44 to one terminal of the battery 33. The other terminal of the alarm 45 45 is connected by a wire 45 to the other terminal of the battery 33. The other terminal of the alarm 43 is connected by a wire 46 to the other terminal of the battery 33. Hence, when the relay has been energized, the alarm 43 will be 50 actuated and will continue actuated until the members 40 and 41 have been manually separated, as above-mentioned.

55 The circuit through the relay is closed by the finger 20 being brought against the button 22

when the hasp arm 15 rises upon turning of the key 13, as the yoke 25 will then be carried up in the groove 17. The circuit is then again opened by closing the lock. In the event that 5 the armored sleeve 26 be cut with a knife or shears, a short circuit will occur between the cutting tool, the sleeve 26 and the wire 25, thus also energizing the relay and the alarm.

Obviously, modifications in form and structure 10 may be made without departing from the spirit and scope of the invention.

I claim:

In a lock comprising a housing having a bolt or the like adapted to be moved longitudinally 15 from one position when the lock is closed to another position when the lock is open, said bolt having a groove in its surface, a strip of insula-

tion mounted in said housing at right angles to said bolt, a contact button on the end of said strip opposite said bolt, a spring finger having one end secured to the opposite end of said strip and normally extending angularly with respect 5 to said strip to provide a space between the other end of said strip and said button, the extremity of said finger registering loosely in said groove and being adapted to be swung alternately into and out of contact with said button with the 10 said movement of said bolt, said button and said strip being adapted to form the two poles of an alarm circuit, the said extremity of said finger registering in said groove being concavely rounded to form a yoke. 15
